US0D1052392S

(12) **United States Design Patent** (10) **Patent No.:** **US D1,052,392 S**
(45) **Date of Patent:** **** Nov. 26, 2024**

(54) **FASTENING DEVICE**

(71) Applicant: **GRIPPLE LIMITED**, Sheffield (GB)

(72) Inventor: **Oliver Sunderland**, Sheffield (GB)

(73) Assignee: **GRIPPLE LIMITED (GB)**

(**) Term: **15 Years**

(21) Appl. No.: **29/893,184**

(22) Filed: **May 25, 2023**

(30) **Foreign Application Priority Data**

Nov. 30, 2022 (GB) 6247256

(51) **LOC (14) Cl.** **08-08**

(52) **U.S. Cl.**

USPC **D8/383**

(57) **CLAIM**

The ornamental design for a fastening device, as shown and described.

DESCRIPTION

FIG. 1 is a perspective view of the fastening device;
FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines in the drawings depict portions of the fastening device that form no part of the claimed design.

1 Claim, 7 Drawing Sheets
